LIFTING JACK

Filed April 27, 1928

INVENTOR
Herman Albertine

BY
George K. Cleall
ATTORNEY

UNITED STATES PATENT OFFICE

HERMAN ALBERTINE, OF EAST RUTHERFORD, NEW JERSEY, ASSIGNOR TO ROGERS PRODUCTS COMPANY, INC., A CORPORATION OF NEW JERSEY

LIFTING JACK

Application filed April 27, 1928. Serial No. 273,190.

My present invention relates more particularly to so-called hydraulic jacks, which comprise piston and cylinder elements operated by hydraulic pressure of a liquid, usually oil, which is pumped into the cylinder space to force the operative expansion or lifting movement of the relatively movable parts and in the present disclosure of the device, the cylinder is fixed and the piston element 10 is the one forced upwardly by the liquid to produce the desired lifting effect. It will be evident that the main features of my invention are highly desirable and that many of its novel features are very useful through 15 a wide range as to power of jacks of this general type.

The hydraulic method of operation makes it easy to apply relatively great lifting effects by relatively small manual effort and such 20 great and easily applied lifting effects are likely to make trouble especially at the end of the lift of the plunger, where further movement must be stopped. For this purpose, mechanical stops have been employed 25 on the cylinder and on the plunger respectively which engage at the upper end of the lifting stroke of the plunger. But in such case continued operation of the pump produces undesirable strains, high pressures and 30 stresses that sometimes wreck the pump. Means for cutting off the power, as by closing the intake to the pump, have also been employed.

My present invention includes means for 35 bypassing the fluid liquid from the output to the intake of the pump when the pressure exceeds a predetermined maximum. This feature serves not only to limit the upward movement of the plunger but also to prevent 40 excessive pressures regardless of the height of the movable element. This will prevent damage to the pump, in certain cases, as where attempt is made to lift a load far in excess of the designed power of the jack.

45 A further feature of the invention is means for adjusting the pressure at which the by-pass relief device begins to operate. Other features of the invention relate to arranging the relief device in the end of the 50 plunger; to the assembly of the relief and

adjusting devices in a single element which may readily be attached to or removed from the plunger; and an arrangement with a chamber surrounding the relief device and communicating through a restricted passage 55 with the space between the outer surface of the plunger and the inner surface of the cylinder, the latter being in communication with a surrounding reservoir that supplies the pump.

Other features and advantages will appear upon consideration of the following description and the accompanying drawings, wherein

Fig. 1 is a view in longitudinal section; 60
Fig. 2 is a view on a larger scale of a detail of Fig. 1; and

Fig. 3 is a view in cross section on the line 3—3 of Fig. 2.

The jack includes a substantial base 10, 70 preferably of cast iron, having a threaded socket 11 which receives the lower end of an upstanding cylindrical member or cylinder 12, preferably a heavy drawn steel tube, forming the outer wall of the annular reservoir 75

13. Countersunk in the bottom of socket 11 is a second socket 14 also threaded and receiving the threaded lower end of a similar cylinder or cylindrical member 15 constituting a guide member in which a plunger 16 is telescopically mounted. The cylinder 12 is closed at the top by a head in the form of a screw plug 17 having a flange which engages the top of the cylinder when these parts are assembled. The head or plug 17 closes the 80 reservoir space at the top and is provided with a central opening 18 to accommodate the plunger or piston 16. The inner wall of this opening is cut away to provide a beveled shoulder 19, cooperating with a screw bushing 20 to retain and compress packing 21. The packing is wedged between the shoulder and the bushing and insures firm non-leak, sliding contact with the plunger. The annular head or cap 17, bushing 20 and packing 85

21 have a guiding and oil wiping function which is more important than their function of preventing leakage since in normal operation there is very little internal pressure in the reservoir.

The guide cylinder 15 is open at the top and the stem of the plunger 16 has a relatively loose fit therein affording an annular space 27 so that the oil can flow in either direction, between said space and the pump reservoir. 5

At its lower end, the plunger 16 has an internally threaded bore 22 and is in engagement with an annular collar or piston head 23, having a close fit in the cylinder 15 and 10 provided with a central bore 24 normally maintained in alignment with the bore 22 in the piston by means to be described more fully hereinafter. This piston head 23, which is preferably of metal, is formed with an annular chamber 25 communicating interiorly 15 with the bore 24 and a restricted passage 26 extends along its upper surface affording an outlet to the annular space 27 between the plunger 16 and the cylinder 15.

Upon the lower face of the annular head 23 20 is an annular washer 28, preferably of leather, which is in turn engaged by a downwardly turned annular cup washer 29, also preferably of leather. The head 23, washer 28 and cup leather 29 are all clamped in position 25 with reference to the plunger stem 16 by means of a bolt element 30 formed with a hollow tubular shank 31 which serves as a valve casing. The shank is exteriorly threaded to fit the bore 22 of the 30 plunger 16 and is provided with a head 32 of greater cross section providing a clamping shoulder 33 which engages a clamping washer 34 the upper surface of which clamps the central portion of the cup washer 29. By screwing 35 the valve casing 30 into the bore 22 of the plunger 16, the piston head and washers are clamped against the lower end of the plunger with the proper degree of pressure. The 40 upper surface of the washer 34 has annular ribs 35 which may be forced into cup leather 29, to hold it securely and to prevent leakage of the liquid interiorly through the central perforation of the cup.

The hollow stem 30 is utilized as the casing of a pressure relief or safety valve. It 45 is provided at its lower end with an axial passage 36 communicating at its upper end with a larger central bore 37 extending downward from the upper end of the stem. At the 50 lower end of the bore 37 and surrounding the upper end of the passage 36 is a conical valve seat 38 provided for co-operation with a valve member or ball 39 to close the passage 36.

This ball 39 is held in the tip of the tapered 55 lower end of a member 40 in a socket which contains slightly more than the upper half of the ball and therefore prevents separation. Preferably, the ball is secured either by brazing 60 or by spinning in the tapered edges of the adjacent cone surface. The upper end of the member 40 is formed with a reduced shank 41 extending upwardly from an annular shoulder 42 and is urged in a direction 65 to close the passage 36 by a helical spring 43 of which the lower end surrounds the shank 41 and engages the shoulder 42 and the upper end engages a screw plug 44 threaded into the enlarged upper end of the bore 37 in the valve casing. Screwing the plug 44 in or out, as by a screwdriver engaging the slot 70 in the upper end of the plug varies the compression of the spring, to set it for any desired tension within the limits of the apparatus. An important point is that the adjustment for a desired relief pressure may be made before the apparatus is assembled and this makes it easy to standardize the operation of all jacks of the same size and lifting power. When the pressure in the cylinder 14 beneath the plunger 16 becomes excessive, the ball valve 39 is forced back against the resistance of the spring 43 thus permitting the liquid to pass upwardly through the passage 36 into the bore 37 and out therefrom through 80 a passage 45 provided for the purpose into the annular chamber 35 and outwardly therefrom through the restricted passage 36 to the annular space 27 from which it can flow back to the reservoir 13. It will be seen that the passage 45 is made of sufficient size to assure communication with the annular chamber 25 regardless of different longitudinal adjustments of the valve casing 30, and that the annular chamber assures communication regardless of angular adjustment of the valve casing. As before explained, complete assembly of the relief valve element and adjustment of the tension of the spring 43 85 may be effected before screwing the tubular shank 31 into the lower end of the plunger. 90

The pumping means for forcing fluid from the reservoir 13 to the interior of the cylinder 15 below the plunger, includes a plunger 46 vertically movable in a cylinder 47 formed in a lateral extension 48 of the base 10. At the lower end of the cylinder 47 is a conical valve seat 49 adapted to cooperate with a valve member or ball 50 to form a check valve and prevent liquid drawn into the cylinder 110 47 through a passage 51 extending from a reservoir 13 to the valve seat 49, from returning to the reservoir when the pump plunger 46 is depressed. At its lower end, the pump plunger 46 is provided with a 115 cupped flexible washer 52 held thereagainst by a screw 53 so as to avoid leakage past the head of the piston or plunger when it is depressed during a pumping action. During such downward movement of the plunger 47, liquid drawn into the cylinder 47 from the reservoir 13 will be forced from the cylinder, through a passage 54 and past a check valve 55 into the cylinder 15. 120

As here shown, the check valve 55 is a ball valve and the ball thereof may be kept from movement too far from its seat by a plate 56 having a central opening of less diameter than the diameter of the ball and clamped in position 125

tion between the base and the lower end of the cylinder 15.

In normal operation, the jack is put into use with the plunger 16 in its lowest position and with the liquid in the reservoir at the normal level indicated by a dot and dash line 57 (Fig. 1). Upon reciprocating the pump plunger 56, liquid will be drawn from the reservoir 14 and forced into the lower end of the cylinder 15 and the plunger 16 may be raised to the desired position. If the operation of the pump is continued and the load on the piston 16 does not require an increase of pressure above that for which the relief valve device is set, the plunger will rise until the upper side of the piston head 23 engages the lower face of the head 17. Then continued movement of the pump plunger would effect increase of pressure in the cylinder 15 thus tending to subject parts of the jack to undue stresses. When, however, the pressure for which the relief device is adjusted is reached, the ball 39 will be forced upwardly in the valve casing 30 and the pressure in the cylinder 15 below the plunger will be relieved by passage of liquid therefrom through the passage 36 to the interior of the valve casing 30 and outwardly therefrom through the passage 45, the annular chamber 25 and the restricted passage 26 and over the top of the cylinder 15 to return to the liquid remaining in the reservoir. The plunger is lowered by releasing the oil from beneath the piston through relief outlet 60. This outlet communicates with a valve controlled passage leading back to the reservoir 14. This release passage and its valve are not shown because they are preferably the same as shown in patent to Zabriskie No. 1,611,703.

It should be understood that various changes may be made in the construction and arrangement of the parts without departing from the true scope and spirit of the invention.

I claim:

1. A jack, including an oil reservoir, a cylindrical member constituting the inner wall of said reservoir, a piston in said cylindrical member having a stem guided in said reservoir, a pump for delivering oil from the reservoir to the interior of said cylindrical member, a safety valve in the lower end of said piston to permit escape of oil when the pressure exceeds a predetermined limit, and means for regulating said safety valve to determine the pressure at which it is to be operated, said safety valve and regulating means being a removable unit structure so that it can be separately adjusted for the desired pressure limit while removed from the jack.

2. A jack, including a guide cylinder, a reservoir around said cylinder and communicating therewith at the top, means for pumping liquid from said reservoir into the lower end of said cylinder, a plunger having a loose

fit in said cylinder and provided at its lower end with a threaded axial bore, means at the bottom of the plunger for effecting a liquid tight seal in said cylinder and including an annular head fitting the interior of said cylinder and having a central passage of substantially the same cross section as said bore communicating with an annular passage at the upper surface of said annular head where it engages the lower end of the plunger and a restricted passage extending from said annular passage to the outer surface of said plunger, and a safety valve device having an externally threaded portion passing through said annular head and screwed into said bore in the plunger and having a head by means of which said annular member is clamped against the lower end of said plunger.

3. A jack, including a guide cylinder, a plunger having a loose fit in said cylinder and provided at its lower end with a device fitting said cylinder closely and having a passage therethrough from the bottom side thereof upwardly to the lower end of said plunger and outwardly through a restricted section to the outer surface of the plunger to form a by-pass and a safety valve assembly extending through said by-pass device into the lower end of the plunger and adapted to prevent the passage of fluid from said cylinder through said by-pass until a predetermined pressure is exceeded.

4. A jack, including a guide cylinder, a plunger having a loose fit in said cylinder and provided at its lower end with a device fitting said cylinder closely and having a passage therethrough from the bottom side thereof upwardly to the lower end of said plunger and outwardly through a restricted section to the outer surface of the plunger to form a by-pass and safety valve assembly extending through said by-pass device into the lower end of the plunger and adapted to prevent the passage of fluid from said cylinder through said by-pass until a predetermined pressure is exceeded, said safety valve assembly being in the form of a hollow, exteriorly threaded bolt.

5. A jack, including a cylinder and a plunger, the plunger including a stem of smaller diameter than the cylinder and a piston head fitting the cylinder closely, an annular cup leather below said head, said plunger being formed with an axial passage extending upwardly from the lower end of the plunger and a lateral passage communicating with the space between the stem and cylinder and in combination with said parts a bolt threaded in said axial passage to clamp said cup leather in operative relation to the piston head, said bolt having longitudinal hollow portion formed with a valve seat and housing an overload valve and having a relief passage from the compression cylinder to the valve and an outlet through said lateral

passage into said space between the stem and cylinder.

6. A jack, including a guide cylinder, a plunger having a loose fit in said cylinder and
5 provided at its lower end with a device fitting said cylinder closely and having a passage therethrough from the bottom side thereof upwardly to the lower end of said plunger and outwardly through a restricted section
10 thereof to the outer surface of the plunger to form a by-pass and a safety valve device extending through said by-pass device into the lower end of the plunger and adapted to prevent the passage of fluid from said cylinder through said by-pass until a predetermined pressure is exceeded, said safety valve device including means for adjusting the pressure at which relief will be effected.

7. A jack, including a guide cylinder, a
20 plunger having a relatively loose fit in said cylinder and having an internally threaded axial bore at the lower end thereof, an annular head at the lower end of said plunger fitting said cylinder and having at its upper
25 face an annular chamber communicating with its central opening and a restricted passage from said annular chamber to the outer surface of the plunger, and means for preventing passage of fluid through said washer including a relief valve device having a tubular shank passing through the central opening of said head and threaded into said bore in the plunger, said tubular shank having an opening to communicate with the annular
30 chamber in said washer and said relief valve device having at the lower end of said shank a spring controlled relief valve.

8. A jack, including a guide cylinder, a plunger with packing to form a piston, having an internally threaded axial bore at the lower end thereof, and a restricted passage from said bore chamber to the outer surface of the plunger above the packing and means for preventing passage of fluid through said
40 bore and passage, including a relief valve device having a tubular shank threaded into said bore in said plunger, a valve seat and valve in said valve device at the upper end of a passage communicating with the interior
45 of the cylinder, and means for yieldably holding said valve member against said seat, including a helical spring in said shank and screw plug adjustably threaded into the upper end of said tubular shank and engaging
50 the upper end of said spring.

Signed at New York, in the county of New York and State of New York, this 26th day of April, A. D. 1928.

HERMAN ALBERTINE.
